United States Patent Office.

THOMAS B. WEBSTER, OF SEKAUKUS, NEW JERSEY.

Letters Patent No. 88,246, dated March 23, 1869.

IMPROVEMENT IN AUTOMATIC BOILER-FEEDERS.

The Schedule referred to in these Letters Patent and making part of the same.

To all whom it may concern:

Be it known that I, THOMAS B. WEBSTER, of Sebaukus, in the county of Hudson, and State of New Jersey, have invented a new and useful Improvement in Boiler-Feed Regulators, of which the following is a full, clear, and exact description, reference being had to the accompanying drawing, forming part of this specification, and which represents a sectional elevation of an automatic boiler-feed regulator, constructed in accordance with my improvement, as applied to a steam-boiler.

My improvement embraces an automatic device for regulating the feed or supply of water to the boiler, and maintaining the same at a uniform or safe level in the boiler, even though the force-pump, which keeps up the supply, continues to operate after the water has reached its desired level in the boiler.

The invention consists in a combination with a check-valve, or valves to the feed-pipe of a boiler, under control of a float, or its equivalent, connected with the latter, of a surplus-escape valve arranged between the check-valve and force-pump, and kept closed by a piston exposed to the pressure of steam in the boiler, and of greater area than said surplus-escape valve, so that not only is deficiency in the water-supply to the boiler automatically prevented, but, without stopping the pump, excess of feed also avoided, and the surplus water returned, if desired, to the cistern, or source from which the pump draws its supply.

Referring to the accompanying drawing—

A represents the end, or side of a steam-boiler, and a, the ordinary or proper water-level therein.

B is a cylinder, or vessel arranged at any suitable distance from the boiler, and at such altitude, as that on connecting said vessel with the boiler by pipes C D, provided with cocks b b, for opening and closing the connection, the same is made to form steam and water-spaces corresponding with those in the boiler.

Within the chamber, or vessel B, is a hollow spherical, or other suitable float, E, properly guided or directed, and, if necessary, provided with attachments, or constructed to free itself of steam or water collecting within it.

The float-rod c, which projects outwardly through the cover of the vessel B, is attached, at its upper end, to a beam, or lever, F, having its fulcrum, as at d, and carrying or having connected with its outer arm, a rod, e, that, as the float E rises, serves to close a check-valve or balance-check valves, f f, in or to an advance feed-pipe, G, which is closed at its end, g, so that water cannot pass to the boiler by a secondary or connecting-pipe, G', excepting through said valves, that may be adjusted in relation to the float by a screw-coupling, h, on the rod e.

Connected with the advance pipe G, or coupling, connecting a divided construction thereof, in advance of the check-valves f f, is a cylinder, or vessel, H,

which communicates with said pipe by an opening, i, covered by a surplus-escape valve, k, opening outward, and which, when open, permits water to escape from the feed-pipe G, out through a discharge-pipe, or aperture, l, back, if desired, to the cistern, or source from which the feed, or force-pump draws its supply, so that no water need be wasted, or lost.

This valve k is kept closed by a piston, m, arranged to operate within the cylinder H, and exposed to the pressure of steam in the boiler, by connection of said cylinder, through a pipe, n, either with the steam or water-spaces of, or connections from the boiler.

Said piston m is of somewhat greater area than the valve k, which it controls, so that when the check-valves f f are open, the pressure on the valve k, to keep it closed, will be in excess of the pressure acting in an opposite direction to open it.

The operation is as follows:

Supposing the water to stand in the boiler at the desired level, or rather to fall below said level, then the valves f f, being open, or opened by the action of the float E, and valve k closed by the action of the piston m, water is forced into the boiler by the pump, first through the pipe G, and subsequently through the secondary pipe G', but on an excess of water being supplied to the boiler, the valves f f are closed by the float, and the water forced into the pipe G by the pump made to lift or open the valve k against the action of the pressure from the boiler on the piston m, and such surplus water discharged through the pipe, or aperture, l, back to the water-tank, or elsewhere.

In this way may the pump be constantly kept running, but the feed to the boiler made to regulate itself, so as to maintain a proper level of water in the boiler, the device not merely protecting the boiler against deficiency, but also against excess of supply, and in the latter case, without loss, or waste of the surplus water.

The usual risks of stopping the pump when sufficient water has been forced into the boiler, and of starting it again when the supply has fallen short, are done away with, by keeping the pump continuously running, which, furthermore, adds to its efficiency.

It may here be observed, that in the working of the device, when the valves f f are not sufficiently opened by the float to pass the water through them as fast as it is forced in by the pump, then the valve k opens to carry off the surplus.

What is here claimed, and desired to be secured by Letters Patent, is—

The surplus escape valve k, closed by pressure of steam on the piston m, in combination with the check-valve f and float E, and arranged between said check-valve and the feed-pump, substantially as specified.

THOS. B. WEBSTER.
